UNITED STATES PATENT OFFICE.

EXEL EKBLOM, OF LONDON, ENGLAND.

SAFETY-BLOCKS FOR BOAT-FALLS AND OTHER PURPOSES.

Specification of Letters Patent. Patented May 19, 1914.

1,096,831.

Application filed May 12, 1913. Serial No. 767,201.

To all whom it may concern:

Be it known that I, EXEL EKBLOM, a citizen of the United Kingdom of Great Britain and Ireland, and resident of 76 Avenons road, Plaistow, London, England, have invented certain new and useful Improvements in Safety-Blocks for Boat-Falls and other Purposes, of which the following is a specification, such as will enable others skilled in the art to which it appertains to make and use the same.

This invention relates to improved safety blocks or pulleys and is particularly designed for use with boat falls on board ship, the object of the invention being to make or provide the said blocks or pulleys with means which will prevent them turning over when the weight of the boat is removed.

It is well known that when boats are lowered from davits at the side of a ship that after the boat has been released and the falls are being pulled up on to deck again for the purpose of attaching them to another boat, the bottom blocks or pulleys, that is to say those next to the boat, frequently turn over and in doing so twist the ropes and mix same so that it is not possible to properly pull back the rope and when this occurs the whole fall is usually pulled on to deck by grasping the ropes between the top pulley (the pulley on the davit) and the bottom pulley, after which the ropes are straightened and properly gathered so as to permit correct lowering of the next boat. This straightening of the ropes and re-adjustment of the falls involves serious delay and requires considerable deck room and it is to obviate this confusion of the ropes that my invention is primarily de-

signed.

My invention may be broadly described as consisting in providing the bottom blocks or pulleys with improved means which will keep them from twisting or falling over. A suitable way to accomplish this is to provide one or more guide plates or equivalents of known or suitable form on each bottom block through which one or more lengths of rope are passed, the said plate or equivalent being on the upper end of the pulley and to connect the said two bottom blocks to each other by any suitable means and also if desired, to weight the lower end of the pulleys. A simple construction is to provide on the top of the pulley a plate extending sidewardly and having in it one or

more holes through which the rope is passed. The plate may be of any suitable size and while I preferably use a three sheave pulley or block I find it is only necessary to provide a plate having two holes, one on each side, through each of which one of the lengths of the rope is passed. Two of these bottom blocks are used as usual and I join them together by a cord, bar or the like. The weight if used may be of any suitable shape and be fixed to the pulley in any desired manner.

I will now describe my invention with reference to the accompanying drawings, in which—

Figure 1 is a top view of an ordinary sheave pulley block *a* to which a double guide plate *b* is fitted. The drawings also show in dotted lines a side extension *c* to which a rope or the like could be attached for the purpose of joining a pair of blocks together as shown diagrammatically in Fig. 4. Fig. 2 is a side elevation of the block shown in Fig. 1 and Fig. 3 is a side elevation of Fig. 2.

In Figs. 2 and 3 a weight *d* is shown on the inside of the block above the loop *e* upon which the boat is hung. It will be observed that the plate *b* acts as a guide to the center cord on the block and it will be obvious that as this cord passes through the holes *b'* on the guide plate *b* on opposite sides of the block the latter can not easily turn and so twist the ropes or if it should be turned it will quickly re-adjust itself so that the ropes hang correctly.

In Fig. 4 a pair of two sheave blocks are shown supporting a boat. These have guide plates *b* and side extensions *c*, the said extensions being joined together by a rope or equivalent *f* upon which a weight *g* is placed, the tendency of the said weight being to draw the blocks toward each other and thereby prevent them from twisting.

What I claim and desire to secure by Letters Patent is—

1. In combination a pair of boat falls each comprising a block, a plurality of pulleys mounted on the block, a rope passed around the said pulleys and guides through which the rope passes mounted on the block, lateral extensions on the block and a rope directly connecting the free ends of the extensions together.

2. In combination, a pair of boat falls each comprising a block, a plurality of pul-

leys rotatably mounted therein, a guide plate fitting around said block and provided with a lower loop, a lateral extension pointing toward the other block and a pair of 5 guide arms having terminal holes, a rope passing around said pulley and through said holes, a weight in said lower loop, and an eye suspended from said loop; a rope connecting the free ends of said extensions; 10 and a weight at the center of said rope.

3. In combination, a pair of boat falls each comprising a block, a plurality of pulleys rotatably mounted therein, a guide plate fitting around said block and provided 15 with a lower loop, a lateral extension point-

ing toward the other block and a pair of guide arms having terminal holes, a rope passing around said pulley and through said holes, a weight in said lower loop, and an eye suspended from said loop; a rope 20 connecting the free ends of said extensions; and a weight at the center of said rope, said arms and extension being perpendicular to each other.

In witness whereof I have hereunto set 25 my hand in presence of two witnesses.

EXEL EKBLOM.
